(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof; and,

FIG. 5 is a fifth image thereof.

The outermost broken lines in the figures show a display screen or portion thereof, and form no part of the claimed design.

The other broken lines in the figures show portions of the animated graphical user interface that form no part of the claimed design.

The subject matter in this patent includes a process or period in which an image changes into another image. The process or period forms no part of the claimed design.
